US00D847774S

(12) **United States Design Patent** (10) **Patent No.:** **US D847,774 S**
(45) **Date of Patent:** **** May 7, 2019**

(54) **MOBILE PHONE**

(71) Applicant: **HUIZHOU TCL MOBILE COMMUNICATION CO., LTD.**,
Huizhou, Guangdong Province (CN)

(72) Inventors: **Hagen Fendler**, Huizhou (CN); **Yongde Xu**, Huizhou (CN); **Liang Zhang**, Huizhou (CN); **Liangjian Chen**, Huizhou (CN); **Fuqiang Ye**, Huizhou (CN)

(73) Assignee: **HUIZHOU TCL MOBILE COMMUNICATION CO., LTD.**,
Huizhou, Guangdong Province (CN)

(**) Term: **15 Years**

(21) Appl. No.: **29/592,133**

(22) Filed: **Jan. 26, 2017**

(30) **Foreign Application Priority Data**

Jan. 13, 2017 (CN) 2017 3 0014071

(57) **CLAIM**

The ornamental design for a mobile phone, as shown and described.

DESCRIPTION

FIG. 1 is a perspective view of a mobile phone;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The repeated circular features present on the back of the mobile phone in FIGS. 1 and 3-7 depict a pattern on the surface that does not have depth.

The dot-dash broken lines in drawings represent boundaries of the claimed design. The area inside of the dot-dash rectangle on the front of the mobile phone and beneath the

(Continued)

outer transparent cover forms no part of the claimed design. The dash-dash broken lines in drawings depict environmental subject matter that forms no part of the claimed design. All of the above mentioned broken lines form no part of the claimed design.

1 Claim, 7 Drawing Sheets
